UNITED STATES PATENT OFFICE.

STEPHEN KRONBURGER, OF JERSEY CITY, NEW JERSEY, ASSIGNOR TO COHAN-EPNER CO. INC., OF NEW YORK, N. Y.

DESIGN FOR A COMBINATION ASH TRAY AND MATCH-BOX HOLDER.

61,343.

Specification for Design.

Patented Aug. 8, 1922.

Application filed May 5, 1921. Serial No. 467,226. Term of patent 7 years.

To all whom it may concern:

Be it known that I, STEPHEN KRONBURGER, a citizen of the United States, residing at Jersey City, in the county of Hudson and State of New Jersey, have invented a new, original, and ornamental Design for a Combination Ash Tray and Match-Box Holder, of which the following is a specification, reference being had to the accompanying drawings, forming part thereof.

Fig. 1 is a perspective view of my combination ash tray and match box holder, looking down upon the ash container thereof showing an opening for a match box in the rear thereof; and Fig. 2, is a perspective view of my combination ash tray and match box holder, showing its side.

I claim:

The ornamental design for a combination ash tray and match box holder, as shown.

STEPHEN KRONBURGER.
